DESIGN FOR A DRAFTSMAN'S COMPASS

Charles D. Stewart, Glendale, Calif.

Application August 22, 1938, Serial No. 79,485

Term of patent 7 years

To all whom it may concern:

Be it known that I, Charles D. Stewart, a citizen of the United States, residing at Glendale, in the county of Los Angeles and State of California, have invented a new, original, and ornamental Design for a Draftsman's Compass, of which the following is a specification, reference being had to the accompanying drawing, forming part thereof.

Figure 1 is a side elevational view of the draftsman's compass, showing my new design; and Figure 2 is an edge elevational view thereof.

I claim:

The ornamental design for a draftsman's compass, as shown.

CHARLES D. STEWART.
